CONVEYOR MEANS FOR ROTARY OFFSET PRINTING MACHINES

James J. Trier, Elmsford, N. Y., assignor to R. Hoe & Co., Inc., New York, N. Y., a corporation of New York

Application December 30, 1953, Serial No. 404,460

6 Claims. (Cl. 101—177)

This invention relates to offset printing presses, and more particularly to such presses designed for multi-color printing on sheet metal or other relatively heavy and stiff material.

In equipment of this character, the sheet carrying or forwarding mechanism is of a different character than in the usual sheet-fed offset press. Instead of the transfer cylinders or chain conveyors found in offset presses designed for printing on sheets of paper, a sheet metal press requires substantial tractive and supporting mechanism and moreover requires a greater range of adjustment between the sheet carrying mechanism and the blanket and impression cylinders; for any change in thickness or flexibility of the sheets being printed requires a change in the relation of the sheet forwarding devices to these cylinders. The mechanism between units as herein disclosed permits free access to the printing units for the necessary operational adjustments and replacement of printing plates, blankets and packing.

In the best multi-color sheet metal printing presses heretofore known the successive printing units have been positioned at progressively lower levels so that the sheet travels in an inclined plane in passing through the press. This very largely increases the height of the machine, especially at the point where it receives sheets. Also, a solid support for the elevated units must be provided, with corresponding increased weight and expense for the frame structures. The drive connections are necessarily somewhat complicated and standardization of units can be achieved only to a limited extent.

It is an object of the present invention to provide a horizontally aligned group of printing units while still affording access to the units.

A second object is to provide an improved arrangement for adjusting the relation of sheet conveyor mechanism to the printing couples.

A further object is to provide a press composed of standard and interchangeable units.

A still further object is to provide an improved drive arrangement.

With these objects, as well as still other objects, which will appear in the following description, the invention consists in the combinations and arrangements of parts, and details of construction, which will now first be fully described with reference to the accompanying drawings and then be more particularly pointed out in the appended claims.

In the drawing:

Fig. 1 is a side elevation of a printing machine embodying the invention in a preferred form;

Fig. 2 is a plan view of the machine of Fig. 1, printing cylinders and associated inking mechanisms being omitted so as to show more clearly the remaining structure;

Fig. 3 is an enlarged side elevation view of one of the units of Figs. 1 and 2.

In Figs. 1 and 2, there is shown a press including a sheet feeder A, four successive printing units B, C, D and E, and a delivery F.

2

Each unit (C, for example) has plate, blanket and impression cylinders (10, 11 and 12) and an ink motion and water motion indicated generally at 13 and 14. As will be understood, the cylinders will be equipped with the usual mechanism for holding plates and blankets and will have the usual tripping mechanisms. These details may be conventional, form no part of the present invention and hence are not shown or described herein.

The relative positioning of the blanket and impression cylinders is important, the axes of these cylinders being in a close to vertical plane, which, however, is slanted by a small angle (about 7° in the construction shown). In consequence, the tangent plane to the blanket cylinder 11 and impression cylinder 12 at the printing point is slanted to the horizontal plane of approach of the sheet by this same angle, arching or wrapping the sheet slightly on the impression cylinder. The forward edge of the sheet emerging from the line of impression is directed downwardly by a similar angle and encounters an upwardly slanted adjustable section 20 of the sheet conveyor between units, gradually rising to the original horizontal plane until, by the time it has passed the impression line its forward edge is again in that plane. The leading edge of the sheet thus travels in a horizontal plane except for a dip and rise as it leaves a unit.

As shown in Figs. 2 and 3, the conveyor section 20 comprises a frame composed of side elements 21 connected together by shafts or rods 22, 23 on which are rotatively mounted pulley wheels 24 carrying conveyor belts 25. Shaft 22 is rotatively journaled in side frame elements 26 of the machine. The conveyor section 20 is thus pivotally supported by the shaft 22 and it is provided with a handle 32 for manually swinging it between the raised position shown in solid lines in Fig. 3 and the lowered position shown in dotted lines. This arrangement permits the pressman to walk into the space made available when the conveyor section is lowered, and make any needed adjustments or perform any other necessary operations on the unit. Means is provided for counterweighting the conveyor section by an arrangement including at each side of the machine, a link 27 pivotally connected at 28 to a side element 21 and to a crank arm 29 that is secured on a cross shaft 30 journaled in the frame elements 26 at each side of the machine. The links 27 as herein shown each consists of a lower section 27A, and an upper section 27B, which are screw threaded and joined by a turn-buckle sleeve 33 that provides means for adjusting the effective length of the link. Weights 31 which are secured to the shaft 30 are lowered when the conveyor section is raised and consequently the effort required to raise it is greatly reduced. Stop screws S are positioned to engage the weights 31 and are adjustable to limit the upward movement of the conveyor section.

Means for securing the outer end of the conveyor section 20 when it is raised to the upper position, is provided as herein shown, by adjustable latches L formed with hooks L2 which engage studs L1 secured to ears 34 projecting from side members of the said conveyor section at each side of the machine. These latches are adjustably secured to arms L3 of bell crank levers having hubs L4. Each hook L2 is provided with a slot L6 and a bolt secured to the arm L3 passes through the slot and is provided with a wing nut L7 which serves to clamp the parts together in the position required for proper adjustment.

The hubs L4 are secured to a shaft L5 journaled in the side frames of the machine, and have other arms formed with handles L8 for manual operation of the latches. A tension spring L9 urges the bell crank levers and the latches carried thereby into position to engage the studs L1 when the conveyor section is raised to its upper posi-

tion. It will be understood that the latch will then snap over the pin and hold the conveyor securely.

An upper cross cat-walk section 35 is provided, and is carried by brackets 36 pivotally mounted to the frame sections 26, and formed with lugs 37 and 38 engaging studs 39 in both the full line and dotted line positions of the figure so as to position this cat-walk element, both in the operating position (full lines) and in the swung back position (dotted lines), which moves this element out of the way to permit the operator to get at the unit.

Further platform elements on the operating side of the machine include platforms 40 somewhat below the cross cat-walks 35, together with steps 41, 42 and 43. Suitable railings 44 are provided in conjunction with these platforms.

On the drive side of the machine a continuous walk is provided, this walk including for each unit sections 45 and 46, all of which sections are horizontally aligned and which are provided with a railing 47 carried in stanchions 48 mounted on the walk sections 45. Access may be had to this walk by means of a step 49.

The machine drive comprises for each unit a unit drive shaft 50, a gear box 51 having a short shaft section 52 which is connected by coupling 53 to further shaft sections 54 between units, and 55 leading to the delivery. This entire drive arrangement is positioned under the walk 45-46 and within the outline thereof in plan, providing a compact construction. Gear box 51 adjacent the sheet feeding end of the machine is provided with a drive shaft 60 carrying a drive pulley 61 and which is driven by belt 62 from a pulley 63 carried on the shaft of a motor 64. The motor shaft and drive shaft 60 both extend transversely of the machine and the motor, together with its belts, are positioned within the extended plan profile of the walk 45-46. The sheet feeder 65 is conventional, and requires no special description. It should be noted, however, that since the printing units are horizontally aligned, the unit need not be elevated as in the best previous presses of this type, so that the sheet feeder likewise need not be elevated, very much simplifying its support.

As will be apparent from the drawing and the foregoing description, the various units may be of standardized construction and may be assembled readily upon a level bed plate 70 (Fig. 1), constructed and supported in any convenient manner. Each unit has its own frames 71 and 72 fixed to the bed plate as indicated. Additional conveyor frame structure comprising upper horizontal members 73 bolted or otherwise fixed to the unit frame structure and to the vertical frame elements 26 previously referred to are also provided. The bed plate may be formed as indicated in plan in Fig. 3, being composed of similar sections, each extending from an end having fastening flanges 75 and 76 to an opposite end having two legs 77, 78 between which is an opening accommodating the weights 31 as well as other mechanism. A lower walk 80 extending across the unit above this opening is provided.

What is claimed is:

1. A metal decorating offset press comprising a plurality of horizontally aligned offset printing units arranged for printing successively upon a sheet and conveyor means for forwarding a sheet from a printing unit to the next printing unit comprising a conveyor section immediately adjacent a unit for receiving a sheet therefrom, a pivotal mounting supporting the said section for movement between an operating position and a non-operating position and to permit a workman to stand in the space between the pivotal mounting and the preceding printing unit which is normally occupied by the said section, when in operating position, a cross walk above the said section for furnishing access to the upper part of a unit, and a

pivotal mounting supporting the cross walk in a horizontal position and in a swing back position.

2. A metal decorating offset press comprising a plurality of horizontally aligned offset printing units arranged for printing successively upon a sheet and conveyor means for forwarding a sheet from a printing unit to the next printing unit comprising a conveyor section immediately adjacent a unit for receiving a sheet therefrom, a pivotal mounting supporting the said section for movement between an approximately horizontal operating position and an approximately vertical non-operating position to permit a workman to stand in the space between the pivotal mounting and the preceding printing unit which is normally occupied by the said section, when in operating position, and adjustable means for holding the said section in operating position and adjusting its angular position slightly about said pivotal mounting to regulate its height adjacent the printing unit, the last said means comprising yielding means for urging the said section toward operating position and means for holding the said section in operating position.

3. A metal decorating press according to claim 2, in which the said yielding means comprises a counter balance weight.

4. A sheet metal printing press comprising an aligned interchangeable plurality of successive printing units together with means for conveying a sheet through the said successive printing units, bed plate structure supporting the said units and additional frame structure for the conveyor means between the said units, unit drive shafts extending transversely of the line of units, a main drive shaft extending along the line of units at one side thereof, gearing connecting the main drive shaft to the unit drive shafts, a drive motor located at an end of the line of units and within the extended plan profile thereof, a drive connection between said motor and the main drive shaft, and a platform extending along the drive shaft side of the machine and overlying the said main drive shaft.

5. A metal printing press comprising in combination a printing unit and conveyor means for taking sheets therefrom, the said conveyor means comprising a section immediately adjacent a printing unit, means pivotally mounting the said section for swinging movement about an axis spaced from the unit, mechanism for supporting the said section in an approximately horizontal sheet conveying position and dropping it into an approximately vertical position to permit access to the unit by a pressman, and adjustable means for varying the first said position, whereby the height of the line of engagement of the leading edge of the sheet with the said conveyor section as it comes in contact therewith upon emerging from the printing unit may be adjusted, the said adjustable means comprising a pair of links, connected to the said section, means for adjusting the length of the said links, a shaft, cranks carried by the shaft and connected to the links and yielding means urging the cranks to urge the said section toward operating position.

6. A metal decorating press according to claim 5, in which the yielding means comprises a counterweight carried by the said shaft and positioned for movement near dead center when in non-operating position.
